UNITED STATES PATENT OFFICE.

THOMAS J. HUNT AND MAE E. WALKER, OF ALAMEDA, CALIFORNIA.

SUBMARINE MINE.

984,674.

Specification of Letters Patent. Patented Feb. 21, 1911.

Application filed June 15, 1910. Serial No. 567,060.

To all whom it may concern:

Be it known that we, THOMAS J. HUNT and MAE E. WALKER, citizens of the United States, residing at Alameda, in the county 5 of Alameda, State of California, have invented a new and useful Submarine Mine, of which the following is a specification.

This invention has reference to improvements in submarine mines and its object is 10 to provide a means whereby submarine mines may be readily controlled from the shores of comparatively constricted waterways such as entrances to harbors and the like.

15 The invention is particularly applicable to situations where the water currents are strong, whether such currents be due to tidal or other conditions, and to this end the invention comprises a cable track for a carriage or carriages carrying torpedoes or submarine mines, which track may be elevated or depressed at will by suitable mechanism located on the shore, the carriage for the torpedo or mine being weighted to maintain 20 its position irrespective of the strength of current flow, while impelling cables are provided whereby the torpedo may be moved along the track to any desired position, the mine or torpedo being fixedly 25 connected to the carriage so as to be readily directed where wanted.

The invention will be best understood from a consideration of the following description taken in connection with the accompanying drawings forming a part of 30 this specification, in which drawings:—

Figure 1 is a view representing a constricted waterway and showing the manner of applying the invention thereto. Fig. 40 2 is a more or less diagrammatic view showing the manner of applying the invention to a constricted waterway and illustrating the operation of the invention.

Referring to the drawings there is shown 45 a cable track 1. This track in the form of a cable is connected at each side of a waterway to a winding drum 2 which may be under the control of suitable power mechanism so that the cable way may be rendered 50 taut or slack at the will of an operator. The drums 2 and operating mechanism therefor are housed in suitable defenses 3 on each shore of the waterway so as to be free from harm.

55 The cableway 1 is designed to receive a carriage 4 provided with wheels or rollers

engaging the cable track or way 1 so that the carriage may be easily moved from point to point as may be found expedient. There will of course be as many carriages 4 as 60 may be desired so that there may be disposed upon the track or cableway 1 as many carriages as are found necessary to protect the channel. Each carriage has mounted thereon a torpedo or submarine mine 6 of 65 any suitable character adapted to be exploded either by contact or by electric current furnished from the shore, both these types of torpedoes or submarine mines being commonly employed.

70 The carriage 4 extends below the cable 1 and may there be provided with weighting material 7 which will render the carriage sufficiently heavy to maintain the torpedo or mine 6 in a substantially upright position even when the water currents are swift, the cable track 1 being sufficiently strong to resist the strain imposed by the action of the current on the carriage 4. There is also provided another cable 8 extending 75 from suitable winding drums 9 in the fortifications 3 and this cable 8 is made fast to the carriage 4 so that upon the proper actuation of the drums 9 the carriage 4 is impelled from point to point along the cable 80 or track 1.

When it is desirable that the torpedo or mine 6 should be inactive then the cable track 1 is slackened until the carriage 4 with the torpedo 6 is lowered to the bottom of the 90 channel or is lowered sufficiently so that no vessel will come in contact therewith, the impelling cable 8 being correspondingly slackened. Under these conditions vessels may 95 pass along the waterway without danger of harm from the torpedo. If however it be desirable to destroy a vessel, say an enemy's vessel attempting to enter the harbor protected by the mines, then the cable 1 is raised by being wound on the drum or drums 100 2 until the cable 1 is taut and the carriage 4 is raised with it, so that under these conditions the torpedo or mine 6 is within striking distance of the hull of any vessel passing over it.

105 The officer in charge may readily move the carriage 4 along the track 1 to the proper position to engage the vessel it is intended to attack and the mine may be exploded in any of the usual manners.

110 Where it is desirable a number of carriages 4 may be mounted on the cable track

1 and attached to the impelling cable 8 so that the channel is traversed by a series of closely adjacent mines some one of which must be engaged by a passing vessel when 5 the mines are in the elevated position.

By making the carriage 4 rigid and the mine or torpedo 6 rigidly connected therewith and also by weighting the carriage, water currents will have no material effect 10 upon the carriage or torpedo even when such currents are strong and the officer in charge of the defense is assured of the proper relation of the torpedo or mine 6 to the surface of the water irrespective of the current conditions. 15

It will be understood that the showing of the drawings is largely diagrammatic and that the invention is by no means limited to the structure there shown but may be variously modified so long as the salient features are retained. 20

It is to be noted that the cable 8 is connected with the weighted end 7 of the carriage 4, below the cable 1, and that the drums 9 25 constitute an independent means for advancing the cable 9 longitudinally, and for putting the same under longitudinal strain. Presupposing that the carriage has been lowered into the position shown in dotted 30 line in Fig. 2, it will be seen that by manipulating the drums 9, the cable 8 may be drawn taut, the cable 1 remaining slack. By this operation, the carriage 4 will be turned end for end, upon the cable 1 as an axis, thus 35 disposing the weighted end 7 of the carriage uppermost. When the carriage is thus positioned, the torpedo will be disposed adjacent the bottom of the stream, and out of contact with passing vessels, the operation 40 enabling the mechanism to be so positioned

that should a loyal vessel of unusually deep draft pass through the channel, such vessel will not be injured by the torpedo. Moreover, by tightening the cable 8, and by loosening the cable 1, a vessel may be permitted 45 to pass over the torpedo, until the torpedo is disposed substantially amidships of the vessel, whereupon the cable 1 may be tightened, bringing the torpedo into contact with the keel of the vessel, at a point substantially 50 amidships, or otherwise, thus permitting the torpedo to be exploded directly beneath some specific part of the vessel, say beneath the magazine or the engine room. 55

What is claimed is:—

A submarine mine system comprising a cable track in traversing relation to a water-way, means for placing the cable track under different degrees of longitudinal strain to elevate or lower said track with relation to 60 the surface of the water, a carriage movable along and supported by the cable track and weighted below the cable track, a torpedo or mine in fixed relation to said carriage above the same, and a second cable connected 65 with the weighted end of the torpedo, below the cable track, and independent means for advancing the second cable longitudinally and for putting the same under longitudinal strain to elevate the weighted end of the torpedo 70 above the cable track, when the track is slack.

In testimony that we claim the foregoing as our own, we have hereto affixed our signatures in the presence of two witnesses.

THOMAS J. HUNT.
MAE E. WALKER.
